MATTRESS HANDLE

Edward L. Bronstien, St. Paul, Minn., assignor
to Michael Bechik, St. Paul, Minn.

Application May 5, 1933, Serial No. 669,541

5 Claims. (Cl. 5—345)

The present invention relates to a mattress handle.

An object of the present invention is to make an improved and simplified mattress handle.

5 Another object is to make a mattress handle having ventilating elements incorporated therein.

In order to attain these objects, there is provided, in accordance with one feature of the invention, a mattress handle having a rigid support member secured to the inner side of a mattress wall, and having a pair of openings adjacent the ends of said member registering with openings in the mattress wall. A handle member is passed through the openings in said rigid member and said mattress wall and the inner ends of said handle member are secured against displacement interiorly of said rigid member, to hold the handle member closely adjacent to the mattress wall.

These and other features of the invention will 20 be more fully brought out in the following description and the accompanying drawing, wherein:

Figure 1 is a view in perspective of a corner portion of a mattress having a handle embodying the present invention mounted in a side wall of said mattress.

Figure 2 is a fragmentary view in perspective of a portion of a mattress wall having a handle embodying the present invention mounted therein and disclosing the inner side of said wall; and

30 Figure 3 is a sectional view on the line 3—3 of Figure 2.

Referring to the drawing in detail, a strip A of metal, which may be strap iron, has an inwardly curved central portion 1 with straight end portions 2 and 3. Each of the straight end portions is provided with an opening therethrough, the openings in the present case being elongated. Eyelets 4 and 5 are inserted in the openings in the straight portions 2 and 3 of the bracing member

40 A and these eyelets pass through openings in the mattress wall 6 and are riveted at both ends to securely clamp the mattress wall to the bracing member A. In the present instance, ventilating screens 7 and 8 are mounted, one in each of the

45 eyelets 4 and 5, and smaller eyelets 9 and 10 are mounted at the inner ends of each of the larger eyelets 4 and 5, respectively. These smaller eyelets 9 and 10 are of a size to freely receive a cord handle member 11 which passes through the

50 smaller eyelets 9 and 10. Washers 12 and 13 of a size to overlap the sides of the opening in the eyelet members 4 and 5 are threaded onto the ends of the cord 11 and retaining collars 14 and 15 are then mounted over the ends of the cord to rest

55 against the inner surfaces of the washers 12 and

13, respectively. Split rivets 16 and 17 are forced through the collars 14 and 15 and through the ends of the cord 11 to firmly secure the cord to the collars 14 and 15.

The mattress wall 6 is of a conventional type 5 having layers of fabric 18 and 19 on each side of a central cotton batt member 20. Two rows of split rivets 21 unite this structure on each side of the central portion thereof and a row of stitching 22 is preferably provided between the openings 10 for the eyelets 4 and 5 so as to compress this portion of the mattress wall to facilitate the grasping of the handle 11 by a user. Normally, the handle cord 11 lies along the face of the mattress wall and closely adjacent thereto. When it is desired 15 to grasp this handle the fingers of a user, not shown, are inserted beneath the cord, the curved portion A of the bracing member permitting the portion of the mattress wall 6 overlying the curved central portion 1 of the member A to be displaced 20 inwardly, thereby facilitating the insertion of the fingers of the user beneath the cord. By means of this construction the necessity for springs, or other means heretofore provided, to permit the handle cord 11 to be moved away from the wall 25 of the mattress is eliminated, and a strong handle, economical in construction and attractive in appearance, is provided.

I claim:

1. In combination with a mattress wall having 30 a pair of comparatively large openings therein, a rigid bracing member positioned interiorly of said wall and having an aperture in each end thereof to register with said wall openings, a ventilating eyelet mounted in each of said openings, said eyelet being partially screened and partially open, a handle eyelet mounted in the open portion of said screened eyelet, and a flexible handle passing through each of said handle eyelets and having the portion thereof between said eyelets normally 40 in contact with the mattress wall.

2. In combination with a mattress wall, a bracing member positioned interiorly of said wall and having an aperture at either end thereof, eyelets extending through said apertures and through the 45 mattress wall to secure said bracing member to said mattress wall, screening means extending partially across the openings in said eyelets, handle means extending through said eyelets and having the portion thereof between said eyelets 50 normally against the mattress wall, and means on either end of said handle means to anchor said handle means to said bracing member.

3. In combination with a mattress wall, a bracing member positioned interiorly of said wall and 55

having an aperture at either end thereof, eyelets extending through said apertures and through the mattress wall, said eyelets being partially screened and partially open, and handle means extending 5 through the open portion of said eyelets and having the portion thereof between the eyelets normally in contact with the mattress wall.

4. In a mattress handle, in combination with a padded mattress wall, screened eyelets adapted to 10 extend through said mattress wall, a flanged head portion on the end of said eyelets adjacent the screen portion thereof for gripping the mattress wall on the outside thereof, a substantially rigid bracing member extending longitudinally internally of said wall, adapted to receive the inner ends 15 of said eyelets to form a spacing and bracing means for holding said eyelets apart, and preventing the collapsing of said eyelets against the

padded wall of the mattress to permit free ventilation through said eyelets, and a flexible handle outside of said mattress wall supported by said eyelets.

5. In combination with a padded mattress wall, 5 screened eyelets having enlarged flanged heads, a flexible handle supported by said eyelets along the outside wall of the mattress, and a comparatively rigid reinforcing member extending longitudinally along the inside of said mattress wall 10 and adapted to provide an anchoring means for the inner ends of said eyelets and forming a support and bracing member for said eyelets and handle to prevent folding of the padded mattress wall and closing off the ventilation through said 15 eyelets by any strain directed to said mattress wall.

EDWARD L. BRONSTIEN.
